D. C. BROWN.

Running-Gear.

No { 2,562, }
33,566. }

Patented Oct. 29, 1861

Inventor:
D. C. Brown
by his Attorney
A. B. Letts

UNITED STATES PATENT OFFICE.

D. C. BROWN, OF NEW YORK, N. Y.

IMPROVEMENT IN RUNNING-GEAR FOR FOUR-WHEELED VEHICLES.

Specification forming part of Letters Patent No. 33,566, dated October 29, 1861.

To all whom it may concern:

Be it known that I, D. C. BROWN, of the city, county, and State of New York, have invented certain new and useful Improvements Appertaining to the Running-Gear of Four-Wheeled Vehicles; and I do hereby declare that the following is a full, clear, and exact description of the construction and operation of the same, reference being had to the annexed drawings, making a part of this specification, in which—

Figure 1 is a top view, the dotted lines showing the outlines of the toothed segments through the cap; Fig. 2, a top view with the cap removed; and Fig. 3, a longitudinal elevation.

The object of my invention is to enable me to use large forward wheels under circumstances that will admit of turning the carriage within a very narrow compass. To this end the hind wheels are made to follow the precise track marked out by the forward wheels in attempting to turn or to avoid an object; and no further care is demanded from the driver than to see that the forward wheels are given the proper direction.

To enable others skilled in the art to make and use my invention, I will proceed to describe its construction and operation.

The main reach A, constructed with an enlarged circular part B at its center, serving as a bed for the superincumbent mechanism, is attached at each end to the axles by means of mortises through the said axles and king-bolts a a. This admits of both sets of wheels turning about the king-bolts as centers, the mortises being long enough to yield a motion of limited extent. Frames or supplemental reaches C C proceed from the axles, being framed therein at their outer ends toward each other, and nearly meet at the center of the main reach. On the under sides of these frames and near their inner ends are formed circular tracks b b, which travel in ways c c of a corresponding shape, while upon their upper sides and directly over the tracks and ways are arranged so as to gear the toothed segments D and E. One of these toothed segments D is of irregular formation, having a large and long tooth d interposed between the smaller teeth and an eccentric e in the rear. It is held to its frame by means of a

single screw or bolt f, which allows of a motion about that as a center to the extent of the slots g, through which project pins or detents h h. The other toothed segment E is also irregular in shape, to the extent of having an open space for the gear of the large tooth of segment D; but it differs from D in being fixed to its frame by screws or bolts i i.

In the main reach in rear of segment D is made a mortise k, and in the cap F, which secures and protects the mechanism, is formed another mortise l, coincident with the mortise k in the main reach. These, together with the horizontal hole through the rear leg of the cap, which receives its shank, (see G, Fig. 3,) serve as guides to the sliding button or detent H, which is kept up to its work with the eccentric e by means of the coiled spring m.

The operation of this apparatus is as follows: The rear axle being at right angles with the main reach, the sliding spring button or detent H is held firmly up into the depression of the eccentric e, and preserves that axle in that position against ordinary obstructions in the road. The large tooth d also assists in effecting this result, and it is, moreover, essential in maintaining the gear, inasmuch as the segment D turning upon two centers—viz., upon the rear king-bolt and upon the screw or bolt f—the pitch of the teeth must be such as to correspond with the different circles described. The segment D is made movable or has given to it a certain degree of dead or lost motion for the purpose of accommodating the front wheels to the natural sway or movements of the team; but when it is necessary to turn the carriage the power of the team overcomes this dead or lost motion and the force of the sliding spring button or detent, and the segments continuing to act upon each other the axles are brought to corresponding angles, so that the rear wheels travel in the same path or circle as the front wheels, as represented by the red line in Fig. 2. As to the tracks b b and ways c c, these perform an important function, inasmuch as if both king-bolts be lost or broken, they serve to keep the axles always in their relative and proper positions. The king-bolts are, in fact, of little use, except for additional security.

Having thus described my invention, and pointed out the manner in which it operates,

what I claim therein as new, and desire to secure by Letters Patent of the United States, is—

1. The toothed movable segment D and segments E, in combination with the sliding spring button or detent H, when constructed and operating substantially as and for the purpose above set forth.

2. The movable segment D, when constructed and operating as described to yield to the

forward axle and wheels a limited motion independent of that imparted to the hind axle and wheels.

3. The tracks b b and ways c c, in combination with the frames or supplemental reaches C C, as and for the purpose described.

D. C. BROWN.
